(57) **CLAIM**

The ornamental design for an ear tip, substantially as shown and described.

DESCRIPTION

FIG. 1 is a perspective view of an ear tip for the right ear of a user, as seen from the front, top, and left side, “left” being from the observer’s point of view;

FIG. 2 is front view thereof;

FIG. 3 is a right side view thereof;

FIG. 4 is a back view thereof;

FIG. 5 is a left side view thereof;

FIG. 6 is a top end view thereof;

FIG. 7 is a bottom end view thereof;

FIG. 8 is a perspective view of a second implementation of an ear tip, for the left ear of a user, as seen from the front, top, and right side;

FIG. 9 is front view thereof;

FIG. 10 is a right side view thereof;

FIG. 11 is a back view thereof;

FIG. 12 is a left side view thereof;

FIG. 13 is a top end view thereof; and,

FIG. 14 is a bottom end view thereof.

The ornamental design is shown on one ear tip, for the right ear of a user, in FIGS. 1 through 7. A mirror-image of the design would be used for an ear tip for the left ear, as shown in FIGS. 8 through 14.

In the drawings the claimed design is defined by surface boundaries as illustrated by solid connected line portions and surface contours as illustrated by unconnected line portions. The dotted line portions of the drawings represent environmental structure only and do not form part of the claimed design.
